UNITED STATES PATENT OFFICE.

GOTTLIEB J. HESS, OF LINCOLN, NEBRASKA.

HOT-WATER STOVE.

SPECIFICATION forming part of Letters Patent No. 761,482, dated May 31, 1904.

Application filed December 11, 1902. Serial No. 134,817. (No model.)

To all whom it may concern:

Be it known that I, GOTTLIEB J. HESS, a citizen of the United States, residing at Lincoln, in the county of Lancaster and State of Nebraska, have invented new and useful Improvements in Hot-Water Stoves, of which the following is a specification.

My invention relates to hot-water stoves; and the object of the same is to construct a device of this character for use in heating rooms by the use of gas, gasoline, kerosene, or electricity, which stove will supply sufficient moisture to the room to make it a healthful place to live in.

15 The simple and novel construction employed by me in carrying out my invention is fully described and claimed, and illustrated in the accompanying drawings, forming a part thereof, in which—

20 Figure 1 is a plan view of my stove with the cover removed. Fig. 2 is a vertical longitudinal section taken on the line 2 2, Fig. 1. Fig. 3 is a plan view of the base. Fig. 4 is a broken horizontal section on the line 4 4, 25 Fig. 2.

Like numerals of reference designate like parts in the different views of the drawings.

The numeral 1 designates the base of my stove, which consists of a flanged ring 2, perforated at 3 to permit the entrance of air. Mounted in the ring 2 and supported thereby is a water-tank 4, comprising two annular portions in axial alinement—a lower one 5 and an upper one 6. The ring 6 has an outer diameter which is smaller than the outer diameter of the ring 5, but larger than the inner, so that they overlap to form benches 7 and 8 and communicate through an annular opening 9. The cylindrical aperture 9^a in the center of the lower ring 5 forms a chamber to accommodate a burner 10, and the aperture 12 in the center of the upper ring 6 forms a draft-opening to permit the ascent of the hot air.

Located above the base 1 and in alinement therewith is a cylindrical tank 13 and open at the top 14 and having a bottom comprising a central plane circular portion 15, surrounded by a downwardly-extending rim 16, located in alinement with the front face of the bench 8,

and an annular plane portion 16^a, extending 50 parallel to the upper face of the bench 7 and of equal inner and outer diameters.

A removable circular cover 17, having a rounded top highest in the middle, is fitted on the tank 13. The cover 17 is apertured at 18 55 to accommodate a pipe 19, which establishes communication between the tank 13 and an open urn 20, mounted on the top of the tank and containing a sponge 21. This construction enables the steam from the water in the 60 tank 13 to keep the sponge saturated with water, which will keep the air in the room charged with moisture. To enable water to circulate from the lower tank to the upper and back, two sets of vertical pipes are provided—an 65 outer set 22, which extend between the bench 7 and the annular portion 16^a and establishes communication between the bottom of the upper tank 13 and the bottom portion of the lower tank 4, and a set of pipes 23, which 70 connect the bench 8 and the central portion 15 of the bottom of the tank 13 and establish communication between the top of the tank 4 and the upper half of the tank 13.

When my stove is in use, the tanks 4 and 75 13 are filled with water up to within a couple of inches of the lower edge of the cover 17 and the burner 10 lighted. The burner 10 will heat the air above it, which will rise and warm the room. A fresh supply of air will 80 flow in through the perforations 3 and be heated in passing up by the burner. The water in the pipes 23 and the tank 4 will be warmed by the burner, that in the upper portion 6 of the tank 4 being heated the most. 85 This hot water will rise through the pipes 23 and flow into the upper portion of the tank 13, where it will become gradually cooler and will be displaced by the warmer water flowing in and will sink and find its way down through 90 the pipes 22 and flow into the bottom portion 5 of the tank 4 and will then rise to the upper part through the opening 9. In this manner the circulation will continue.

I do not wish to be limited as to details of 95 construction, as these may be modified in many particulars without departing from the spirit of my invention.

Having thus described my invention, what I claim as new, and desire to secure by Letters Patent, is—

1. In a stove of the character described, a lower water-chamber, an upper water-chamber, a combustion or heating chamber, and water-pipes establishing communication between said lower and upper water-chambers, said lower chamber having a stepped inner wall, forming said heating-chamber and its exit-flue, and having a corresponding upper wall, the steps of which, have connected thereto the lower ends of said pipes, respectively.
2. In a stove of the character described, a lower water-chamber having a stepped inner wall and a corresponding outer wall, an upper water-chamber having a stepped lower portion or bottom, and water-pipes establishing communication between said lower and upper water-chambers, said water-pipes connecting with the respective steps of the outer wall of said lower chamber, and, in like manner, with the steps of the lower portion or

bottom of said upper water-chamber, respectively, and a heating-chamber, arranged in 25 the base of the stove.

3. In a stove of the character described, a heating or combustion chamber, a lower water-chamber having an inner stepped wall and a corresponding outer wall, a base having air-inlets therethrough, in a plate below said combustion-chamber, an upper water-chamber having a stepped lower portion or bottom, and series of water-pipes establishing communication between said lower and upper water-chambers, connecting with corresponding steps of said lower and upper water-chambers, respectively.

In testimony whereof I have hereunto set my hand in presence of two subscribing witnesses.

GOTTLIEB J. HESS.
